United States Patent Office

Des. 204,715
Patented May 10, 1966

204,715

HUMIDIFIER HOUSING

Warner W. Martin, Olmstead Falls, Ohio, assignor to The Lau Blower Company, Dayton, Ohio, a corporation of Ohio

Filed Apr. 29, 1965, Ser. No. 85,025

Term of patent 14 years

(Cl. D62—4)

FIG-3

FIG-5

FIG. 1 is a perspective view of the humidifier housing, showing my new design;

FIG. 2 is another perspective view thereof;

FIG. 3 is a front elevation view thereof;

FIG. 4 is a bottom view thereof; and

FIG. 5 is a top view thereof.

The portions shown in broken lines are included for illustrative purposes only.

I claim:

The ornamental design for a humidifier housing, substantially as shown and described.
